UNITED STATES PATENT OFFICE.

GEORGE P. RISSEY AND ALBERT P. WILLIAMS, OF SEATTLE, WASHINGTON.

METAL-CUTTING MACHINE.

1,300,879.

Specification of Letters Patent. Patented Apr. 15, 1919.

Application filed October 16, 1917. Serial No. 196,838.

To all whom it may concern:

Be it known that we, GEORGE P. RISSEY and ALBERT P. WILLIAMS, citizens of the United States, residing at Seattle, in the 5 county of King and State of Washington, have invented certain new and useful Improvements in Metal-Cutting Machines, of which the following is a specification.

This invention relates to metal cutting 10 machines, and its object is to provide a device of this character which is designed, more particularly, to be employed in cutting off superfluous ends of bolts driven through a ship's hull to afford proper lengths for 15 riveting.

A further object of the invention is to provide for the operative mechanism a supporting frame provided with means for engaging the work and also having braces for 20 maintaining the machine in operative position.

The invention consists in the novel construction, adaptation and combination of parts, as will be hereinafter described and 25 claimed.

In the accompanying drawings, Figure 1 is a view in side elevation showing an embodiment of the present invention illustrated as applied. Fig. 2 is a plan view of 30 the same. Fig. 3 is a front elevational view thereof. Fig. 4 is a fragmentary longitudinal vertical section taken through 4-4 of Fig. 3. Fig. 5 is a detail sectional view through 5-5 of Figs. 1 and 2.

Referring to the drawings, the reference 35 character B designates a bolt driven through a frame member 6 of a vessel's hull, it being required to cut said bolt off at the plane indicated by broken lines $\alpha-\alpha$ in Fig. 1 at 40 a suitable length for riveting.

In carrying out our invention we provide a frame consisting in a girder member 7 having at one end a head element 8 provided with a front face 9 disposed in substantially rectangular relations to the girder member 7. Formed in one side of said head element is a finger 10 provided at its underside with a notch 11 adapted to hook over the bolt, as represented in Fig. 3. This 45 finger serves also as a jaw in coöperation with an opposing jaw 12 formed on the end of a lever 13 fulcrumed by a pin 14 and is regulated by means of a screw 15 engaging in a threaded aperture provided in the end 50 of the lever. The screw 15 is operated by a hand wheel 16 and impinges against a lug

17 provided on the frame member 7, as shown in Figs. 1 and 2.

The gripping end of the jaw 12 is desirably serrated to afford teeth 18. The fulcrum pin 14 is carried by a vertically movable plate 19, which is secured at adjusted elevations by means of bolts 20 passing through elongated slots 21 provided in the plate and holes 22 provided in ears 23 formed on the frame member 7.

The purpose of vertically adjusting the plate 19 is to locate the height of fulcrum pin 14 so as to present the jaw face 12¹ in substantially rectangular relations to the frame member 7 for various diameters of bolt B.

Formed or provided on the frame member 7 are standards 24 in which are journaled a shaft 25. Mounted on this shaft is a sleeve 26 constituting part of a rotatable frame having at one end a radially disposed arm 27 and at its other end a wheel 28 which is provided with worm teeth 29. Secured in the arm 27 and wheel 28 and in parallel relation with the axis of shaft 25 is a bushing 30 which serves as a journal bearing for a saw arbor 31.

31 represents a circular saw mounted on a collar 32 which is rigidly secured to the forward end of the arbor 30, said saw being detachably connected to the collar 32 as by means of a set screw 33 (Fig. 4) engaging in a threaded hole in the arbor end.

34 represents a spur gear wheel secured to the rear end of said arbor and driven by means of a toothed pinion 35 which is desirably formed integral with the shaft 25.

The feeding movements of the saw are regulated by revolvably moving the same 95 through the agency of a feed screw 36 engaging in the worm wheel element 28 of the aforesaid rotary frame; said feed screw is journaled in bearings 37 provided on the frame member 7, and is manipulated from one side as by means of a crank handle 38.

The shaft 25 is rotated by means of a motor, indicated by broken lines M in Fig. 1. Said motor is desirably of the pneumatic type, one end of its shaft being coupled 105 with the polygonal end 25¹ of shaft 25, such coupling serving to support one end of the motor while its other end is supported as by the provision of a standard 40 projecting upwardly from the rear end of the frame 110 member 7.

The front end of the frame is supported

by the finger 10 engaging over the work or bolt B which is to be cut off. For supporting the rear end of the frame we employ extensible braces, one on each side, each consisting of a rod 41 having at one end an eye 42 whereby it is hingedly connected to an apertured lug 43 depending from the adjacent side of the frame. Said rod extends into a tube 44 provided with a tapering screw-threaded extremity 45 which engages in a tapering screw-threaded hole of a nut 46. The tapered end 45 of a rod is furthermore provided with longitudinal slots 47 so that by screwing down the nut 46 the tube 15 44 may be clamped in adjusted position with respect to the associated rod 41.

Rigidly secured to the end of the tube 44 remote from its tapered end is a rod element 48 terminating in a point 49 adapted to 20 penetrate in the vessel wall or frame member 6. The rod member 48 is also provided with a branch element 50 which may be utilized to cause the penetrating point 49 to become engaged by driving with a hammer against the face 50¹. Said branch may also be utilized to disengage said penetrating point by using a pry bar against its face 50².

The operation of the invention is as follows:—

30 The operator first engages the hooked finger 10 over the end of the bolt B so as to have the end or face 9 of the head element 8 bear against the frame 6. He then adjusts and engages the supporting braces for the 35 rear end of the frame as above explained, and then regulates the lever 13 by means of screw 15 to cause the jaw 12 to firmly grip the bolt B. The motor is then actuated to 40 drive the shaft 25, thereby effecting through the medium of the gears 35 and 34 the rotation of the saw 31.

The operator then manipulates, through 45 crank handle 38, the screw 36 to revolve the saw in the direction indicated by arrow y in Fig. 3; this may be done quite rapidly until the saw is brought into cutting relation with the bolt and thence by a slower movement until the saw is progressively carried through the bolt to cut the same off.

50 The invention is quite simple in its construction and operation, and affords an extremely efficient manner of performing an operation which hitherto has been done by the use of a so-called hand hack-saw or other 55 manually operated tools.

What we claim, is—

1. A machine for cutting off bolts, comprising a machine frame, a saw mounted for

reciprocatory movements thereon, means to effect such movements of the saw, means to 60 rotate the saw, a clamping jaw provided on the frame, a lever pivotally connected to the frame and having a jaw element thereon, and means for actuating said lever to cause the jaw element thereof to coöperate with 65 the first-named jaw to clamp the frame to a bolt which is to be cut off.

2. A machine for cutting off bolts, comprising a machine frame, a saw mounted for reciprocatory movements thereof, means to 70 effect such movements of the saw, means to rotate the saw, a clamping jaw provided on the frame, a lever pivotally connected to the frame and having a jaw element thereon, means for actuating said lever to cause the 75 jaw element thereof to coöperate with the first-named jaw to clamp the frame to a bolt which is to be cut off, and means for regulating the position of the pivotal connection of said lever with the frame to accommodate 80 bolts of different diameters.

3. A machine for cutting off bolts, comprising a circular saw, an arbor therefor, a rotary frame carrying said arbor eccentrically of the axis of said frame, a power- 85 driven shaft extending axially through the latter, gears operatively connecting said shaft with the arbor for driving the saw, a machine frame supporting said rotary frame and the shaft, bolt-clamping means for 90 securing the machine to the bolt, and adjustable means coöoperating with said bolt-clamping means for supporting the machine frame in operative position.

4. A machine for cutting off bolts, comprising a circular saw, an arbor therefor, a rotary frame carrying said arbor eccentrically of the axis of said frame, a driving shaft extending axially through the latter, gears operatively connecting said shaft 95 with the arbor for rotating the saw, a machine frame supporting said rotary frame and the shaft, said machine frame having at one end a laterally directed hook element adapted to be engaged over a bolt for suspending the machine therefrom, and means coöoperating with said frame element for 100 clamping the machine to the bolt.

Signed at Seattle, Wash., this 9th day of October, 1917.

GEORGE P. RISSEK.
ALBERT P. WILLIAMS.
